(57) **CLAIM**

The ornamental design for a stand for a sensor, as shown and described.

DESCRIPTION

FIG. 1 is a right side perspective view of a stand for a sensor in accordance with my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines in the figures are for the purpose of showing environmental structure and form no part of the claimed design.

1 Claim, 4 Drawing Sheets

FIG. 1

FIG. 2

FIG. 3

FIG. 4**FIG. 5**

FIG. 6
